UNITED STATES PATENT OFFICE.

DENNIS LEONARD, OF CLEVELAND, OHIO, ASSIGNOR TO THE CLEVELAND BURIAL CASE COMPANY, OF SAME PLACE.

DESIGN FOR A CASKET-HANDLE.

SPECIFICATION forming part of Design No. 18,816, dated December 18, 1888.

Application filed October 18, 1888. Serial No. 288,471. Term of patent 7 years.

To all whom it may concern:

Be it known that I, DENNIS LEONARD, a citizen of the United States, residing at Cleveland, in the county of Cuyahoga and State of Ohio, have invented and produced a new and original Design for a Handle for a Burial-Casket, of which the following is a specification, reference being had to the accompanying drawing, forming part thereof, which shows a

10 side elevation.

A represents the lugs or plates, B the arms, and C the handle-bar suspended from the arms. The handle-bar is ornamented at its ends, and between the ornamental ends the bar is shaped to represent a series of balls, 15 approximately spheres, joining each other.

What I claim is—

A design for a handle-bar of a burial-casket, consisting of ornamental ends and a series of approximately-spherical formations or balls 20 between the ends and constituting the body of the handle-bar, substantially as shown.

In testimony whereof I sign this specification, in the presence of two witnesses, this 2d day of October, 1888.

DENNIS LEONARD.
